(57) **CLAIM**

The ornamental design for a brassiere strap pad, as shown and described.

DESCRIPTION

FIG. 1 is a perspective view of the present invention shown in use with a brassiere on a model (the model shape and brassiere depicted in broken lines form no part of the claimed design);

FIG. 2 is a perspective view of the present invention;

FIG. 3 is a top view of the present invention;

FIG. 4 is a side view of the present invention;

FIG. 5 is a bottom view of the present invention;

FIG. 6 is a left end view of the present invention, the right end being a mirror image thereof; and,

FIG. 7 is a cross section view of the present invention taken at line 7—7 of FIG. 6.
